UNITED STATES PATENT OFFICE.

VICTOR H. PALM, OF BUTLER, PENNSYLVANIA.

OIL-WELL DEVICE.

No. 875,372.

Specification of Letters Patent.

Patented Dec. 31, 1907.

Application filed July 12, 1907. Serial No. 383,452.

To all whom it may concern:

Be it known that I, VICTOR H. PALM, a citizen of the United States of America, residing at Butler, in the county of Butler and State of Pennsylvania, have invented certain new and useful Improvements in Oil-Well Devices, of which the following is a specification, reference being had therein to the accompanying drawing.

10 This invention relates to improvements in oil well devices, and the invention has for its primary object to dispense with the ordinary sucker rods employed for operating a working barrel valve, and to provide novel 15 means whereby the cable or continuous connection can be used for operating a working barrel valve. To this end, I have devised a novel stuffing box adapted to be located above the working barrel of an oil well, the 20 stuffing box being constructed whereby it can be easily removed from a working barrel at any desired time or located in the well whereby it cannot be accidentally displaced.

The detail construction entering into my 25 invention will be presently described and then specifically pointed out in the appended claims.

In the drawings, Figure 1 is an elevation of my improved device, Fig. 2 is a vertical sectional view of the same, Fig. 3 is a horizontal sectional view taken on the line $x-x$ of Fig. 2, Fig. 4 is a similar view taken on the line $y-y$ of Fig. 2, Fig. 5 is a perspective view of one of the locking members, Fig. 6 is a vertical sectional view of a buffer or block used in connection with the device, Fig. 7 is a plan of the stand pipe of the device, and Fig. 8 is a plan of a clamp used in connection with the stand pipe.

40 In the accompanying drawings, 1 designates the tubing of a well in which is located a working barrel 2 having a lower standing valve 3 and a working barrel valve 4. Connecting with the upper end of the working barrel 2 is a cylindrical casing 5, retained within the tubing 1 of the well by resilient arms 6 having their ends loosely mounted in coils 7 carried by the casing 5. The upper end of the casing 5 is threaded, as at 8 and 45 provided with a tapering seat 9.

Screwed upon the end of the casing 5 is an exteriorly threaded housing 10 having circumferentially arranged segment-shaped grooves 11 formed therein, these grooves receiving the depending pins 12 of segment-

shaped blocks 14, said blocks preventing a full rotation of the pipe 17 in either direction.

Screwed upon the housing 10 is an exteriorly threaded cup 15 for holding the flanged end 16 of a stand pipe 17, said stand pipe having its lower end cut away, as at 17^a, to clear the blocks 14 which extend inwardly and lock the lower tapering end 20 of a pipe 19 in the tapering seat of the casing 5. A gland 18 is threaded upon the cup 15 for holding 65 packing (not shown) in engagement with the stand pipe 17. The pipe 19 is connected by a block 20^a with another section of pipe 21, said block 20^a having a rectangular opening 22 formed therein for a plunger 23, which is substantially rectangular in cross section, whereby said plunger cannot rotate in the block 20^a. The upper end of the plunger 23 is connected to a cable 24, which can be provided with a plurality of blocks 25^a to prevent said cable from being cut or injured by the pipe 21. The lower end of the plunger 23 carries a socket 25, by virtue of which said plunger is connected to the working barrel valve 4. 70

Interposed between the lower end of the pipe 19 and the socket 25 is a coil spring 26, said spring being employed for retaining the working barrel valve 4 in a lowered position.

The cable 24 is adapted to be connected to 85 an ordinary walking beam (not shown) employed for vertically reciprocating the working barrel valve 4 to raise oil in the casing 5 and the pipes 20 and 17, the oil passing through openings or perforations 27 formed 90 in the pipe 19.

In operation, the spring 26 is adapted to lower the working barrel valve 4, while the walking beam of an oil well device is adapted to raise the working barrel valve through the 95 medium of the cable 24. The casing 5 will be normally held within the tubing 1 of the working barrel by the resilient arm 6, these arms, however, permitting of the working barrel and casing being removed by efficient 100 pulling power from above the well. It will of course be understood that the stand pipe 17 extends to the top of the well, and to prevent said stand pipe from accidentally rotating, I use a clamp 30 which is secured to 105 the upper end of the stand pipe, also to an object adjacent to the stand pipe, whereby said pipe and clamp cannot rotate. When it is desired to remove the pipe 19, it is only necessary to partially rotate the pipe 17 and 110

2
by virtue of the cut away end of said pipe move the blocks 14. The segment-shaped grooves 11 of the housing 10 move the blocks 14 outwardly releasing the tapering 5 shouldered end of the perforated pipe 19.

It will be observed from the foregoing description, that I have devised novel means whereby an ordinary wire cable can be used for operating the working barrel valve of a 10 working barrel, thus dispensing with the ordinary sucker rods, commonly used for this purpose.

Having fully described my invention, what I claim and desire to secure by Letters 15 Patent, is—

1. The combination with the tubing of an oil well, the working barrel thereof, and the working barrel valve, of a casing connecting with said working barrel and fixed within 20 said tubing, a stuffing box carried by the upper end of said casing, a perforated pipe mounted in the upper end of said casing, a stand pipe surrounding said perforated pipe and held by said stuffing box, a block carried 25 by said pipe, a rectangular plunger movably mounted in said block and connecting with said working barrel valve, a spring interposed between said perforated pipe and said working barrel valve, a cable connecting with the 30 upper end of said plunger and blocks carried by said cable, substantially as described.

2. The combination with the tubing of an oil well, the working barrel thereof, and the working barrel valve, of a casing connecting 35 with said working barrel and fixed within said tubing, a stuffing box carried by the upper end of said casing, a perforated pipe mounted in the upper end of said casing, a stand pipe surrounding said perforated pipe 40 and held by said stuffing box, a block carried by said pipe, a rectangular plunger movably mounted in said block and connecting with said barrel valve, a spring interposed between said perforated pipe and said working 45 barrel valve, and a cable connecting with the upper end of said plunger, substantially as described.

3. In an oil device, the combination with a working barrel and a valve thereof, of a casing

carried by the upper end of said working barrel, a stand pipe extending upwardly from said casing, a stuffing box for holding said stand pipe upon said casing, a perforated pipe arranged in the upper end of said casing and surrounded by said stand pipe, a 55 plunger operating in said perforated pipe and connecting with said valve, a spring interposed between said perforated pipe and said valve, a cable connecting with the upper end of said plunger, means for preventing said plunger from rotating, and means for preventing said stand pipe from becoming disengaged from said casing, due to rotation.

4. In an oil well device, the combination with a working barrel and a valve thereof, 60 of a casing carried by said working barrel, a stand pipe connecting with said casing, a perforated pipe connecting with the upper end of said casing, a plunger slidably mounted in said pipe and connecting with 65 said valve, a cable connecting with the upper end of said plunger, means for normally holding said valve in a lowered position, and means for preventing the rotation of said plunger.

5. In an oil well device, the combination with a working barrel and a valve thereof, 70 of a casing connecting with said barrel, a stand pipe connecting with the upper end of said casing, a perforated pipe located within 75 said stand pipe, a plunger slidably mounted in said perforated pipe and connecting with said valve, and a cable connected to the upper end of said plunger.

6. In an oil well device, the combination 80 with the working barrel, and the valve thereof, of a casing connecting with said barrel, a perforated pipe detachably mounted in said casing, a plunger operating within 85 said pipe and connecting with said valve and means to lock said perforated pipe in said 90 said casing.

In testimony whereof I affix my signature in the presence of two witnesses.

VICTOR H. PALM.
